UNITED STATES PATENT OFFICE.

BENJAMIN F. HUTCHES, JR., OF RIDGEWOOD, NEW JERSEY, ASSIGNOR TO THE AUTOMULTI-
GRAPH CO., OF NEW YORK, N. Y., A CORPORATION OF NEW YORK.

TYPE-WRITER OPERATOR.

No. 888,808.

Specification of Letters Patent. Patented May 26, 1908.

Application filed June 1, 1907. Serial No. 376,802.

To all whom it may concern:

Be it known that I, BENJAMIN F. HUTCHES, Jr., a citizen of the United States, residing at Ridgewood, Bergen county, State of New Jersey, have invented new and useful Improvements in Type-Writer Operators, of which the following is a specification.

This invention relates to a type-writer operator by which letters or circulars written upon the type-writer will be provided with different headings, so that a like text will be automatically addressed to different parties. The machine is provided with one record for the text and with a multitude of records for the different headings. Means are provided for alternately operating the records, so that a different heading record is interpolated operatively between repetitions of the text record. By changing the heading records, the addressees may be selected by the operator in setting the machine, which, after being so set, will automatically write the letters to said addressees.

The type-writer itself, which does not form part of this invention, should be so constructed that it performs automatically all the different functions necessary for repeatedly reproducing a letter or other writing. It should therefore contain automatic means for shifting and returning the carriage, and for rotating the platen. In addition thereto, means should be provided for automatically removing the written sheets from the platen and for so feeding a blank sheet to such platen that it occupies the proper position for starting the next writing. A type-writer of this class is embodied in a co-pending patent application filed by me May 2, 1907, under Serial No. 371,421, while automatic means for removing the written sheets from the platen and for feeding a blank sheet to such platen are embodied in a second co-pending patent application filed by me May 8, 1907, under Serial No. 372,610. It is to be understood, however, that my improved operator may be used with constructions other than those described in the above two applications.

Briefly stated, my invention embodies a magazine adapted to be operatively connected to a type-writer and containing a stack of heading cards, each adapted to so actuate the type-writer, as to write a different address. After a blank sheet has been brought into proper position for starting the

writing, the date is first written by a record which is subsequently re-used for the text of the letter. The date being thus written, the text record is automatically arrested and the heading record is simultaneously started to provide the dated sheet with name, address and account of the addressee. The heading record is then arrested and the text record re-started to write the text or body of the letter. This record also serves to remove the written sheet, to place a new sheet upon the platen, and to write the date upon this new sheet. After this new sheet has thus been dated by the text record, the heading record is re-started to write a different heading upon such sheet. Means are also provided for so setting the type-writer that any specific number of letters with different headings and like text may be automatically written, after which the machine is automatically arrested.

In the accompanying drawings: Figure 1 is a plan, partly broken away, of the heading device; Fig. 2 a longitudinal section on line 2—2, Fig. 1; Fig. 3 a detail of part of the heading record supporting roller; Fig. 4 a detail section through the contact levers; Fig. 5 a left hand end view, partly broken away, of Fig. 1; Fig. 6 a right hand end view of the same; Fig. 7 a detail of one of the heading cards; Fig. 8 a longitudinal section through the type-writer operator; Fig. 9 a plan of part of the operating mechanism; Fig. 10 a plan of part of the automatic switch; Fig. 11 a side view, partly in section, thereof; Fig. 12 a perspective view of Fig. 10, and Fig. 13 a wiring diagram.

A magazine 20 containing a stack of perforated heading records or cards 21, is adapted to be connected to the frame 22 of an automatic type-writer. The connecting means are shown to consist of a pair of pins 23 on box 20 engaging hooks 24 of frame 22. Within box 20 is journaled a feed roller 25 which receives motion in manner hereinafter described. In front of roller 25 there is arranged a table 26 adapted to support the stack of heading cards 21. The parts 25 and 26 are so arranged that roller 25 projects slightly above table 26 which will cause the cards 21 to be supported at their forward end upon such roller. Above roller 25 extends upwardly an inclined partition 27 having a beveled lower edge. The elevation of partition 27 above roller 25 is such that an inter-

vening gap is formed sufficient to permit the passage of a single heading card. To insure a positive engagement between the cards and roller 25, a presser foot 28, weighted as at 29, 5 slidably engages partition 27 by means of U-shaped arms 30 that straddle such partition. Back of feed roller 25 is hung a grooved roller 31 adapted to support the successively advancing heading cards. Roller 31 receives rotary movement from feed roller 25 by gear wheels 32, 33, 34. Intermediate rollers 25 and 31 there is formed a passage for the cards by means of a lower plate 35 and an upper curved guard 36, the latter being secured to 15 partition 27 at 37. By the construction described the bottom card is fed by roller 25 through the passage between plate 35 and guard 36, until it engages roller 31, which, after the card has fulfilled its function of writing the address, will eject the same.

In order to insure a positive engagement between the cards and roller 31, a pair of friction disks 39 are arranged above the ends of such roller. These disks are mounted upon 20 a vertically movable spindle 40 journaled in upright slots 41 of box 20. Spindle 40 is pressed towards roller 31 by a plunger 42 grasping such spindle, the stem 43 of such plunger passing freely through a perforated 25 screw 44 tapped into a cross bar 45 of box 20. A coiled spring 46 encircles stem 43 between screw 44 and plunger 42, so that by manipulating screw 44 the pressure of the plunger against spindle 40 may be readily adjusted.

30 Roller 31 is provided with a number of spaced circumferential grooves 47, and above each of such grooves is arranged a contact lever 48 free to turn on a stationary shaft 49 mounted in box 20 above guard 36. In order to obtain a proper bearing for each lever 48, the latter is fitted upon a flanged hub 50 loosely turning on shaft 49, the hubs 50 being properly spaced by intervening tubular sleeves 51 on shaft 49. A free play for levers 45 48 is permitted by slotting guard 36 below each of such levers as at 52.

Each lever 48 has a contact screw 53 at its free end and a downwardly extending finger 54 intermediate said screw and fulcrum 49. 50 Contact screw 53 is adapted to engage a fixed contact 55 secured to an insulating cross bar 56 of box 20. The parts are so assembled that when an imperforate portion of card 21 passes beneath finger 54, lever 48 will be 55 maintained in its raised position as shown in Fig. 2, so that contact screw 53 is lifted off contact 55. As soon as a perforation 57 of card 21 arrives beneath finger 54, the latter will drop through such perforation to enter 60 an alined groove 47 of roller 31. In this way lever 48 will tilt by gravity until contact screw 53 rests upon contact 55.

Each contact 55 has a U-shaped spring arm 58 adapted to engage a contact button 65 59 of casing 22, when the heading device is

coupled to the type-writer. Buttons 59 are connected to the means for operating the keys of the type-writer in manner herein-after described, so that when the finger 54 of any contact lever 48 enters a perforation of 70 the heading card, a circuit will be closed that operates the corresponding key of a type-writer.

Feed roller 25 receives intermittent rotary movement from the main power-shaft 60 of 75 the type-writer, which is driven by electro-motor 81. The construction is such that either the text record is fed forward by such power-shaft while the heading card 21 is at rest, or vice versa, as will be hereinafter more 80 fully described. For rotating feed roller 25 there is fast on power-shaft 60 a worm 61 engaging worm-wheel 62 loosely mounted on a counter-shaft 63 and constituting the relatively fixed member of a heading card feed 85 clutch. Upon shaft 63 is slidably mounted the movable clutch member 64, adapted to rotate shaft 63 by a groove and feather connection. Member 64 is provided with a circumferential groove engaged by the free end 90 of the armature 65 of an electro-magnet 67, such armature being pivoted at 66. When armature 64 is attracted, shaft 63 will be coupled to shaft 60, while, when electro-magnet 67 is deenergized and the armature 95 is released, shaft 63 will be uncoupled from power-shaft 60. In alinement with shaft 63 there is mounted in bearings 68, 69 of box 20, a worm-shaft 70, which, when box 20 is coupled to casing 22, will be simultaneously 100 coupled to shaft 63. For this purpose shaft 63 is provided with a notch 71 adapted to receive a tongue 72 of shaft 50. Upon shaft 70 is loosely mounted, by a groove and feather connection, a worm 73 influenced by 105 a spring 74. This worm is adapted to be engaged by a worm-wheel 75 fast on the shaft 76 of roller 25. It will thus be seen that as soon as electro-magnet 67 is energized, roller 25 will receive rotary movement from power-shaft 60 by worm 61, worm-wheel 62, coupling member 64, shafts 63, 70, worm 73 and worm-wheel 75. In order to rotate roller 25 by hand, if desired, a knob 77 is secured to one end of shaft 76. By properly turning 115 this knob, roller 25 is rotated to advance a card 21, during which operation worm 73 is by wheel 75 moved along shaft 70 against the action of spring 74, until worm 73 and worm-wheel 75 are brought out of engagement. If roller 25 is subsequently to be rotated from shaft 70, worm 73 will during the beginning of rotation of shaft 63, be screwed into engagement with wheel 75 until the former bears with its hub against bearing 69, 120 whereupon the rotation of roller 25 will commence.

The above described heading device is to be used in connection with an automatic type-writer, such as shown in Figs. 8 and 9, 130

which illustrate the parts necessary for an understanding of the invention. The type-writer actuating mechanism and the paper feeding means are more fully illustrated and described in the above cited patent applications, and do not form part of the present invention.

For each key of the type-writer, such as the character key, the carriage shift key, etc., there is provided a contact lever 78 having a downwardly projecting finger which is adapted to enter a corresponding perforation of an endless record 79 which serves to write the date and the text of the letter. Record 79 is fed through the machine by suitable means operatively connected to a vertical counter-shaft 80 that may be coupled to power-shaft 60. To this effect shaft 60 has a worm 82 engaging a worm-wheel 83 loosely mounted on shaft 80 and forming the relatively fixed member of the record feed clutch. Upon shaft 80 is slidably mounted the movable clutch member 84 which is engaged by the armature 85 of an electro-magnet 86.

Vertically below each contact lever 78 is provided a contact screw 87 tapped into a block 88, each block 88 being in circuit with one of a set of electro-magnets 89. These electro-magnets are by armatures 90 adapted to operate the keys 91 of the type-writer upon the closing of the circuits. Each of the blocks 88 is further connected by wire 92 to one of the pins 59, such pins being in turn in circuit with the contact levers 48 of the heading device. These contact levers correspond in number and arrangement to levers 78, both sets of such levers being connected to a source of electricity, as hereinafter more fully described. Thus it will be seen that the type-writer keys may be either operated by means of the contact levers 78 of the text record or by the contact levers 48 of the heading record.

The means for returning the type-writer carriage and for substituting blank sheets for written sheets, are described in the above cited patent applications and need therefore not be described in this application. It may, however, be stated that a worm 93 transmits motion from power-shaft 60 to the carriage return means, while a worm 94 transmits motion from said shaft to the paper feeding means. Electro-magnet 95 and co-operating electro-magnets 96, 99 control the clutches for said carriage return and paper feed devices.

Automatic means are provided for alternately actuating the type-bars by levers 78 of the text record, and by levers 48 of the heading record, and for preventing all short circuiting. For this purpose there is provided a contact lever 97 controlled by a perforation in the text record 79, and in all respects similar to one of the levers 78. Lever 97, upon engaging such perforation will cause the ar-

rest of the text record feeding means and the simultaneous starting of the heading card feeding means. Likewise, the heading attachment is provided with a contact lever 98 controlled by the heading card as hereinafter described, and which, when lowered, will arrest the heading card feeding means and restart the text record feeding means.

To carry into effect the desired alternate operation of the record and the card feeding means, record feed clutch 83, 84 is alternately opened and closed, while simultaneously the card feed clutch 62, 64 is alternately closed and opened by an electro-magnet 100 having a spring-influenced armature 101. To the latter is pivoted at 102, a spring pawl 103 engaging a metallic or conducting ratchet wheel 104. The latter is flanked by a pair of non-conducting ratchet wheels 105, 106, secured to wheel 104. Wheels 105, 106 are of slightly larger diameter than wheel 104, and are provided with but half the number of teeth of the latter, the teeth of wheel 105, intercalating with those of wheel 106. Wheels 105 and 106 are respectively engaged by contact springs 107 and 108, the springs being secured to an insulating block 109. These springs, when lifted by the teeth of their ratchet wheels 105, 106, are brought into contact with screws 110, 111, respectively, said screws being tapped into a metallic bridge 112. As the teeth of wheel 105 alternate with those of wheel 106, spring 107 will engage contact screw 110, when spring 108 is out of engagement with screw 111, and vice versa. Intermediate springs 107, 108, there are secured to block 109, a pair of additional contact springs 113 and 114, longitudinally split at their free ends to here form two arms. Springs 113, 114 engage with one of said arms the ratchet wheels 105 and 106, respectively, while their other arm is adapted to come into contact with metallic ratchet wheel 104. When the outer arms of springs 113 and 114 engage the teeth of wheels 105, 106, their inner arms are lifted off ratchet wheel 104, while, when the outer arms engage the tooth-recesses, springs 113 and 114 are in contact with ratchet wheel 104. The latter is engaged by a stationary contact 115 secured to casing 22.

The electric connections of the parts thus far described, are as follows: The type-writer operator receives current from any suitable source of electricity by main wires 116, 117. The electro-motor 81 that operates the power-shaft 60 receives current from the positive main wire 116, through wire 119, contact 120, armature 121 of electro-magnet 95, and wire 122, while a wire 123 connects the electro-motor with the negative main wire 117. A wire 124 leads from main wire 116 to the pivots of contact levers 78, while a wire 125 connects the fulcrums of contact levers 48 with wire 122. The contact 55 of

each contact lever 48 is, by wire 92, connected to the corresponding contact 88 on the operator frame, (the springs 58 engaging contact pins 59 being omitted in the wiring diagram). Each contact 88, is, by wire 127, connected to its electro-magnet 89 for operating the type-writer keys, said electro-magnets being connected to a common return wire 128. Contact spring 107 is, by wire 129, connected to the contact 130 arranged below heading card feed lever 97, while contact spring 108 is, by wire 131, connected to contact 132 arranged below record feed lever 98. The bridge 112 adapted to be alternately engaged by springs 107 and 108 is, by wire 133, connected to electro-magnet 100 which serves to intermittently rotate ratchet wheel 104. Electro-magnet 100 is, by wire 134, connected to wire 117. From contact spring 113 leads a wire 135 to electro-magnet 86 of the record feed clutch, while spring 114 is, by wire 136, connected to electro-magnet 67 of the heading feed clutch. Electro-magnets 67, 86 are, by wires 137 and 138, connected to main wire 117. Ratchet wheel 104 is, by contact 115, wire 139 and contact 140, connected to armature 121 that receives its current from wire 116 through wire 119 and contact 120, as above described. Contacts 141, also adapted to be engaged by armature 121, actuate the carriage return means, and do not form part of the present invention.

As has already been stated, there is used for every address, a separate heading card 21, the perforations of which control the operation of the type-writer while the heading is being written. Levers 48 are normally lifted off their contacts by the imperforate sections of the heading cards. If therefore no heading card is interposed between roller 31 and contact levers 48, all such levers will rest upon their respective contacts 55. To prevent all the type-bars from being thus simultaneously operated, which would result in a destruction of the same, means are provided for breaking the current flowing through magnets 89 when no heading card is interposed between roller 31 and contact levers 48. These means consist of an additional contact lever 142 fulcrumed on shaft 49 of the heading device. To lever 142 is secured by insulating plate 143, a slotted metal spring 144. Above spring 144 are arranged a pair of contact screws 145, 146 tapped into insulated contacts 147, 148, which contacts are adapted to engage with their lower ends a pair of contact pins 149, 150 of frame 22. Of these, pin 149 is connected to return wire 128, while pin 150 is connected by wire 151 to wire 117.

Each heading card 21 is, below contact levers 98 and 142, hereinabove referred to, provided at its front and rear edge with a pair of triangular notches 152, 153, each notch having a straight inner edge 154 and

an oblique outer edge 155. The notches are so cut into the cards, that the finger 54 of the record feed lever 98 enters notches 152, 153, near their alined straight edges 154, while the finger 54 of the circuit breaking lever 142 engages the oblique edges 155. As levers 48 makes contact upon their down stroke, while lever 142 makes contact at its up stroke, it is plain that when no heading card is interposed between fingers 54 and roller 31, all the levers 48, 98 and 142 will be lowered, so that the return current of magnets 89 is broken, and the character keys are rendered inoperative. If a card 21 is now fed between fingers 54 and roller 31, the levers 48 will be first lifted off their contacts 55, and afterwards lever 142 will be raised to contact with screws 145, 146, and thereby establish communication between wires 128 and 151. In order to prevent any damage to the machine in case the attendant should accidentally reverse the cards 21 in box 20, the cards are provided opposite to notches 152, 153 with a pair of corresponding notches 152^a and 153^a.

Means are provided for automatically arresting the type-writer operator including motor 81, after the desired number of letters has been written. These means are shown to consist of an electro-magnet 156 having a spring-influenced armature 157 to which a spring pawl 158 is pivoted. The latter engages a conducting ratchet wheel 159 having a non-conducting tooth 160. Ratchet wheel 159 receives current by wire 161 connected to the negative pole of the source of electricity, while a wire 162 leads from armature 157 to main wire 117. Electro-magnet 156 is, by wire 163, connected to wire 133, and by wire 164 to wire 117. It will thus be seen that at each impulse imparted to electro-magnet 100, part of the current will flow from wire 133 through electro-magnet 156 to attract armature 157 simultaneously with armature 101 of electro-magnet 100. The number of teeth of ratchet wheel 159 should be twice as large as the number of heading cards that can be held by box 20, because electro-magnet 156 is attracted twice for each letter written. Ratchet wheel 159 is provided with a pointer 165, playing upon a dial 166, so that the ratchet wheel may be set for any number of copies desired, after the writing of which the machine is thus automatically arrested.

The operation is as follows: An endless record 79 is placed into the operator frame 22, the cards bearing various headings are stacked into box 20, and the pointer 165 is set to the number of such cards. The bottom card 21 should be so placed that contact levers 48 and 142 are raised thereby, while record feed lever 98 engages its contact 132 through notch 152. The machine is now started by closing a main switch 167, ratchet

104 being so set that spring 107 is raised while spring 113 is lowered. In this way the record feed clutch 83, 84 will be closed by electro-magnet 86, the current flowing as follows: from wire 116 through branch 119, contact 120, armature 121, contact 140, wire 139, contact 115, ratchet wheel 104, spring 113, wire 135, electro-magnet 86 and wires 138, 137, to main wire 117. During the writing operation the current of each text record operator lever 78 travels from wire 116 through branch 124, lever 78, contact 88, wire 127, electromagnet 89 common return wire 128, contact 149, spring 144, contact 150 and wire 151, back to the main wire 117. After the date has thus been written by the advancing text record, a perforation in the latter will arrive below the finger of lever 97, so that the latter by descending, closes a circuit, the current flowing from wire 116 through branch 124, lever 97, contact 130, wire 129, spring 107, bridge 112, wire 133, electro-magnet 100 and branch 134 to wire 117. Part of the current will also flow from wire 133 through branch 163, electro-magnet 156 and branch 164 to wire 117. Electromagnets 106, 156 being thus energized, will attract their armatures 101, 157 to advance ratchet wheels 104 and 159, for the space of one tooth. By the partial rotation of ratchet wheel 104, spring 107 will become disengaged from bridge 112, while spring 108 will come into contact with such bridge. Simultaneously spring 113 has been raised off ratchet wheel 104 to break the current energizing electro-magnet 86 and stop the record feeding means, while spring 114 has been brought into engagement with ratchet wheel 104, to start the heading card feeding means, by a current which flows as follows: from ratchet wheel 104 through spring 114, wire 136, electro-magnet 67 and branch 137 to wire 117. While the perforations in the heading card serve to operate type-writer keys 91, the current of each contact lever 48 flows from wire 125, (which is connected to main wire 116), through lever 48, contact 55, wires 92, 127 into electro-magnet 89, the current return being the same as above described. After the heading has been completed, the finger of contact lever 98 will enter notch 153 to close a current which flows from wire 125, through record feed lever 98, contact 132, wire 131, spring 108, bridge 112 and thence through electro-magnets 100 and 156, as above described. In this way ratchet wheel 104 will be again rotated for the space of one tooth to arrest the heading card feed and to simultaneously re-start the text record feed as will be readily understood. The advancing text record will now cause the body of the letter to be written, will then remove the written sheet, replace it by a blank sheet, and finally write the date upon such blank sheet, after which the op-

eration above described will be repeated. When the desired number of letters has been written, insulated tooth 160 of ratchet wheel 159 will become engaged by pawl 158, so that the supply of electricity to main wire 117 is interrupted and the entire machine is arrested.

If it is desired to write envelops only by means of the cards 21, a contact lever 168 is provided which is, by wires 169, 170 connected to wires 131 and 116 respectively. If the complete address has been written up to the accost, lever 168 is depressed by hand to close a circuit which will energize electro-magnet 100 to rotate ratchet wheel 104 and stop the heading record feeding device, before the accost can be written.

It will be seen that by my invention any desired number of letters can be automatically turned out which contain the same text, but are addressed to different parties. These letters are automatically produced by the machine without requiring an operator, and when the last letter has been written, the machine is automatically stopped. In this way time and labor is saved and large numbers of differently headed letters may be quickly and reliably turned out in an automatic manner. Furthermore, as the heading cards are separate from one another, they may be readily changed, and reduced or replenished in number, so that the addressees of any one letter may be easily selected, desirable parties may be added and undesirable parties may be eliminated.

I claim:

1. A type-writer operator provided with means for supporting a series of disconnected heading cards, and means controlled by said cards for actuating a type-writer, substantially as specified.
2. A type-writer operator provided with a text record, a series of disconnected heading cards, and means alternately operated by the text record and heading cards for actuating a type-writer, substantially as specified.
3. A type-writer operator provided with a magazine, a series of disconnected heading cards contained therein, and means controlled by said cards for operating a type-writer, substantially as specified.
4. A type-writer operator provided with a magazine, a series of disconnected heading cards contained therein, and electric circuits controlled by said cards and adapted to operate a type-writer, substantially as specified.
5. A type-writer operator containing a series of perforated stacked disconnected heading cards, levers adapted to engage the card-perforations, and type-writer actuating means in circuit with said levers, substantially as specified.
6. A type-writer operator provided with a

- magazine adapted to contain a stack of heading cards, means for withdrawing the bottom card, and means controlled by said bottom card for operating a type-writer, substantially as specified.
7. A type-writer operator provided with a magazine adapted to contain a stack of heading cards, means for withdrawing the bottom card, a circuit closer controlled by said card, and type-writer operating means controlled by said circuit closer, substantially as specified.
8. A type-writer operator provided with a magazine adapted to contain a stack of heading cards, means controlled by said cards for operating a type-writer, and additional means controlled by said cards for arresting said type-writer operating means, substantially as specified.
9. A type-writer operator provided with a stack of perforated cards, means for successively withdrawing said cards, and means actuated by the withdrawn cards for actuating a type-writer, substantially as specified.
10. A type-writer operator provided with a stack of heading cards, a text record, means for actuating the record alternately with successive cards, and type-writer actuating means controlled by said cards and record, substantially as specified.
11. A type-writer operator provided with a stack of heading cards, a text record, means for actuating the record alternately with successive cards, type-writer actuating means controlled by said cards and record, and type-writer arresting means also controlled by said cards and record, substantially as specified.
12. A type-writer operator provided with a stack of heading cards, a text record, means for actuating the record alternately with successive cards, type-writer actuating means controlled by said cards and record, and means controlled by the record for arresting the record and starting the cards, substantially as specified.
13. A type-writer operator provided with a stack of heading cards, a text record, means for actuating the record alternately with successive cards, type-writer actuating means controlled by said cards and record, and means controlled by the cards for arresting the cards and starting the record, substantially as specified.
14. A type-writer operator provided with a stack of heading cards, a text record, means for actuating the record alternately with successive cards, type-writer actuating means controlled by said cards and record, means controlled by the record for arresting the record and starting the cards, and means controlled by the cards for arresting the cards and starting the record, substantially as specified.
15. In a type-writer operator, a record, a card, a first contact lever engaging the record, a second contact lever engaging the card, an electro-magnet in circuit with both contact levers, and means controlled by the card for breaking said circuit, substantially as specified.
16. In a type-writer operator, a perforated card having a notch, a first contact lever controlled by the card perforations and in circuit with type-writer operating means, and a second contact lever adapted to engage the card-notch and to break said circuit, substantially as specified.
17. In a type-writer operator, a record feed roller, a card feed roller, a power-shaft, and a ratchet wheel for alternately coupling said rollers operatively to said shaft, substantially as specified.
18. In a type-writer operator, a record, a card, a record feed lever engaging the record, a spring in circuit with said lever, a ratchet wheel and a contact adapted to be engaged by said spring, and an electro-magnet in circuit with the contact and adapted to operate the ratchet wheel, substantially as specified.
19. In a type-writer operator, a card, a record, a record feed lever engaging the card, a spring in circuit with said lever, a ratchet wheel and a contact adapted to be engaged by said spring, and an electro-magnet in circuit with the contact and adapted to operate the ratchet wheel, substantially as specified.
20. In a type-writer operator, a record feed clutch, a first electro-magnet operatively connected to said clutch, a first spring in circuit with said first electro-magnet, a second spring, a ratchet wheel adapted to be engaged by both springs, a second electro-magnet in circuit with the second spring, and means controlled by said second electro-magnet for operating the ratchet wheel, substantially as specified.
21. In a type-writer operator, a card feed clutch, a first electro-magnet operatively connected to said clutch, a first spring in circuit with said first electro-magnet, a second spring, a ratchet wheel adapted to be engaged by both springs, a second electro-magnet in circuit with the second spring, and means controlled by said second electro-magnet for operating the ratchet wheel, substantially as specified.
22. In a type-writer operator, a conducting ratchet wheel, a non-conducting toothed wheel connected thereto, a first spring adapted to engage the ratchet wheel and the toothed wheel, a record feed clutch, an electro-magnet controlling said clutch and in circuit with said first spring, a second spring engaging the toothed wheel, a contact adapted to be engaged by said second spring, and a second electro-magnet in circuit with the contact and adapted to operate the ratchet wheel, substantially as specified.
23. In a type-writer operator, a card feed

clutch, a ratchet wheel, a record feed lever operatively connected to the ratchet wheel, means controlled by the ratchet wheel for operating the card feed clutch, and a counting mechanism controlled by the ratchet wheel, substantially as specified.

24. In a type-writer operator, a record feed clutch, a ratchet wheel, a card feed lever operatively connected to the ratchet wheel, means controlled by the ratchet wheel for operating the record feed clutch, and a counting mechanism controlled by the ratchet wheel, substantially as specified.

25. In a type-writer operator, a power-

shaft, a record, a card, a record feed clutch, a 15 card feed clutch, a ratchet wheel alternately controlled by the record and card and adapted to alternately operate said clutches, and a counting mechanism controlled by the ratchet wheel and adapted to arrest the power-shaft, 20 substantially as specified.

Signed by me at New York city, (Manhattan,) N. Y., this 31st day of May, 1907.

BENJAMIN F. HUTCHES, JR.

Witnesses:

WILLIAM SCHULZ,
ADOLPH MINER.
